UNITED STATES PATENT OFFICE.

JAN NESETŘIL, OF PRAGUE, AUSTRIA-HUNGARY, ASSIGNOR TO JOSEPH PRINCE
COLLOREDO-MANNSFELD, OF DOBŘÍS, AUSTRIA-HUNGARY.

REINFORCED-CONCRETE RAILWAY-SLEEPER.

1,138,398.

Specification of Letters Patent.

Patented May 4, 1915.

Application filed March 6, 1914. Serial No. 822,988.

To all whom it may concern:

Be it known that I, JAN NESETŘIL, citizen of the Austro-Hungarian Empire, residing at Prague, II, Austria-Hungary, have invented certain new and useful Improvements in Reinforced-Concrete Railway-Sleepers, of which the following is a specification.

This invention relates to reinforced concrete railway sleepers.

10 The object of the invention is to provide a sleeper which while being of the requisite strength will be to some extent resilient, and will have means by which the correct gage between the chairs or rail supports will be 15 maintained.

The invention comprises the combination with a sleeper of compressed cement and fibrous material, such as asbestos, of a reinforcement and various details hereinafter 20 particularly described and set forth in the claims.

In the accompanying drawings: Figure 1 shows a longitudinal section through one form of sleeper according to this invention; 25 Fig. 2 shows a plan thereof; Fig. 3 shows a cross section; Figs. 4 and 5 show an elevation in section and a plan respectively of details; Fig. 6 shows a longitudinal section of a modified form of sleeper; Fig. 7 shows 30 a cross section thereof; Figs. 8 and 9 show details according to this modification.

The sleeper, Figs. 1 to 5, during its manufacture is provided with a vertical bore at the two places where attachment to the rails 35 takes place, the said bores being adapted to receive bolts 1. Each of these bolts has mounted at its lower end a nut 2 and is formed at the upper end with an integral conical head 3 in order to secure and hold 40 a rail support or chair base 4 in place. The chair base 4 has a bent extension 5 and integral side pieces 6 having openings through which bolts 7 project in such a manner that the latter are adapted to connect the extension 5 with a separate angle plate 8 by means 45 of nuts 10, the said extension and the plate 8 thus lying opposite one another and allowing of the insertion between them of the base of the rail. The angle plate 8 is hereby so 50 formed that it abuts at 9 against a step provided in the chair base 4 and is prevented in this way from displacement. The angle plate is also provided with an extension the latter being in the shape of a loop 11 to 55 which is secured a steel band 12 partly em-

bedded in the sleeper and connecting with the loop and angle plate on the other end thereof, the object of this arrangement being the maintenance of the exact distance of the two rails and also to prevent slackening of 60 the bolts 1.

The reinforcement of the sleeper consists firstly of a rod 13 which is arranged between the two bolts 1 and at each end terminates in a coiled spring 14 embracing the said 65 bolts. This rod, previous to the pressing operation such as pressure in a hydraulic press, to which the sleeper is subjected is placed in a mold and firmly embedded within the cement and asbestos, so that the coils 70 are loose around their bolts, that is, they must allow the bolts 1 to be subsequently inserted. Thus the material adjacent to the bolts 1 is considerably strengthened and attains a certain stability. The second important 75 part of the reinforcement of the sleeper consists of thin rods 15 which are longitudinally embedded in the material and held in position by being threaded through supports or stays 16, of trapezoidal form. The 80 disposition of the rods 15 is clearly shown in Figs. 1 and 3 and from these it will be easily understood that the rods 15 in combination with the rod 13 impart great bearing strength and resistance to the sleeper, 85 while the trapezoidal stays 16 insure the proper disposition of the rods in the sleeper for the maximum resistance to the stresses under which the sleeper is likely to be placed. 90

The reinforcement of the sleeper according to the modification, Figs. 6 to 9, consists of rods 15 as before described but in this case the latter are supported by two different kinds of trapezoidal supports or 95 stays 17 and 18. The supports or stays 17 are approximately of the construction shown with reference to those of 16; they possess, however, projections 19 for the purpose hereinafter mentioned. Each of the supports or stays 18, Figs. 6 to 8, comprises two abutting members of the form of a trapezoid and each support is further formed with two semicircular grooves the two grooves in each member lying exactly opposite the other and thus forming two sleeves 20 which are riveted at 21. Two such supports or stays 18 are mounted below each base plate 22 of the rails, the sleeves 20 serving to receive two pairs of bolts 23 and the latter 105 110

serving as a means for attachment of said rails to chair base 22. The chair base has an overlapping integral extension 22' and a detachable member 22'' lying opposite said 5 extension and being substantially of similar form, the two pairs of bolts 23 projecting through 22' and 22'' and securing the rail. It will be seen that the reinforcement according to this modification provides the 10 immediate means for securing the chair bases and is consequently cheaper than that of the first construction since the steel bands 12 and the rods 13 are dispensed with.

I claim:

15. 1. A reinforced concrete railway sleeper comprising a body of compressed cement and fibrous material, a reinforcement consisting of trapezoidal stays and rods threaded through said stays, chair bases on said 20 sleeper, bolts for holding said chair bases on to the sleeper and means within the sleeper connecting said bolts together for the purpose of maintaining the chair bases at the correct distance apart, substantially 25 as hereinbefore set forth.
2. A reinforced concrete railway sleeper comprising, a body of compressed cement and fibrous material, and having bores for bolts for securing chair bases to said sleeper, 30 and a reinforcement consisting of stays of trapezoidal form, rods threaded through said stays, and a rod terminating in coiled springs surrounding the aforesaid bores, substantially as and for the purpose herein- 35 before set forth.
3. A reinforced concrete railway sleeper comprising a body of compressed cement and fibrous material, a reinforcement consisting of trapezoidal stays and rods threaded through said stays, chair bases on said 40 sleeper, bolts passing through said sleeper for securing the said chair bases thereto, angle plates adapted to be bolted to said chair bases, and a strap connecting the angle plates, substantially as and for the purpose hereinbefore set forth.
4. A reinforced concrete sleeper comprising a body of compressed cement and asbestos fiber, said body having recesses for

chair bases and bores for bolts for holding 50 said chair bases, and a reinforcement embedded in said body consisting of trapezoidal stays, and rods threaded through said stays, substantially as hereinbefore set forth.

5. A reinforced concrete sleeper comprising a body of compressed cement and asbestos fiber, said body having recesses for bolts for holding 55 said chair bases, and a reinforcement embedded in said body consisting of a plurality of trapezoidal stays, and rods threaded through said stays, some of stays having sleeves coincident with the bores in the body, substantially as and for the purpose herein- 60 before set forth.

6. A reinforced concrete railway sleeper, comprising a body of compressed cement and fibrous material, flat stays in the body portion, each stay comprising a horizontal 70 portion and two downwardly and outwardly extended end portions, a plurality of rods embedded in the body portion and extending through openings formed in the stays:

7. A reinforced concrete railway sleeper 75 comprising a body portion of compressed cement, flat stays embedded in the body portion, each stay comprising a flat member formed with transverse openings, and having a horizontal upper portion and downwardly and outwardly inclined end portions, 80 and rods extending through the transverse openings.

8. A reinforced concrete railway sleeper comprising a body of compressed cement 85 and asbestos, flat stays in the body portion, each stay comprising a horizontal portion and two downwardly and outwardly extended end portions, a plurality of rods embedded in the body portion and extending through openings formed in the stays.

In testimony whereof I have signed my name to this specification in the presence of two subscribing witnesses.

JAN NEŠETŘIL.
